Primary Examiner — Garth Rademaker*Assistant Examiner* — Katie Stofko Mroczka(74) *Attorney, Agent, or Firm* — Finnegan, Henderson, Farabow, Garrett & Dunner, LLP(57) **CLAIM**

The ornamental design for a pet treat, as shown and described.

DESCRIPTION

FIG. 1 is a front, top perspective view of a pet treat showing our new design.

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The contrast in shading in the figures represents a contrast in appearance only and does not represent any particular color, material, texture, or finish.

1 Claim, 4 Drawing Sheets(56)
